UNITED STATES PATENT OFFICE.

WILLIAM WRIGHT VINCENT, OF KENOSHA, WISCONSIN, ASSIGNOR TO THE SIMMONS MANUFACTURING COMPANY, OF KENOSHA, WISCONSIN, A CORPORATION OF WISCONSIN.

HEATING DEVICE FOR LACQUERING.

No. 928,291.

Specification of Letters Patent.

Patented July 20, 1909.

Application filed March 8, 1909. Serial No. 482,052.

To all whom it may concern:

Be it known that I, WILLIAM W. VINCENT, a citizen of the United States, residing at Kenosha, in the county of Kenosha and State 5 of Wisconsin, have invented certain new and useful Improvements in Heating Devices for Lacquering, of which the following is a specification.

My invention concerns improvements in 10 devices for holding or supporting bent tubes, pipes, or the like while they are being lacquered during heating by a current of electricity sent directly through the part to be coated.

15 The appliance is especially adapted to holding the bent polished or burnished tubes forming parts of brass bedsteads, and is equipped with shouldered split adjustable electric terminals adapted to fit in and be 20 expanded within the ends of such tubes, whereby to secure effective electrical connections for the efficient application of a current of electricity for heating purposes.

In the accompanying drawings I have illustrated 25 one desirable embodiment of the invention, these drawings forming a part of the specification.

In the drawings, Figure 1 is a side elevation of the lacquering appliance, certain 30 parts being broken away, the tube supported on the terminals being shown partially in section. Fig. 2 is a top plan view of the construction set forth in Fig. 1, with the tube omitted. Fig. 3 is an elevation, partly in 35 section, of one of the split shouldered conductive terminals; and Fig. 4 is a top plan view of the same.

The device includes a flat table 10 supported in any convenient manner, as by a plurality of standards or legs 11. Near one end 40 this table or bench has rigidly fixed thereto an upright tubular terminal 12 split longitudinally at 13 for a considerable portion of its length. At its top end the two parts of the 45 tube or hollow pipe are each supplied with a semi-cylindrical metallic shouldered contact 14 fastened to the tube 12 by suitable screws 15. It will therefore be apparent that as 50 the parts of the split tube 13 are forced apart by a device described hereinafter, the contacting portions 14 will be likewise expanded, it being understood and as is clearly shown in the drawings, the smaller parts of 55 the contacts 14 are at the top, the contacts increasing in size toward the bottom, which

construction enables them to readily accommodate and fit in the ends of tubes of different internal calibers or diameters. Since in the construction of brass or similar metallic beds the tubes or pipes forming parts of 60 the same are of standard dimensions, it is possible to so construct the contacts 14 that the pipe or tube ends of the bedstead will readily rest upon the proper shoulders, the parts of the contacts immediately above such 65 shoulders substantially filling the ends of the tubes.

Inside of the tube 12 and fastened to one of the split parts I provide a block 16 having a threaded aperture 17 accommodating a 70 screw 18 equipped at its outer end with a pivoted handle 19, the inner end of said screw bearing or abutting against the inner surface of the other half or part of the split terminal. It should therefore be apparent 75 that by turning the screw 18 by means of its handle 19 the parts of the terminal 12 and the shouldered contacts 14 mounted thereon may be readily expanded, the same contracting automatically, owing to the resiliency 80 and elasticity of the split terminal, when the screw is turned in the opposite direction. The other terminal 20 is substantially like the terminal 12, being supplied with shouldered contacts 14, and has a portion 21 passing 85 downwardly through a slot 22 in the table, the part 21 below the table being screw-threaded, as is shown in Fig. 1 and supplied with a tightening nut 23 bearing against the bottom face of the table and 90 adapted and capable of fastening this movable adjustable terminal in the desired position. Below this nut is an apertured contact 24 through the aperture of which passes a longitudinally disposed conductive rod 25, 95 the electrical connection between the same and the part 24 being by a set-screw 26 securely fastening the rod to the contact.

As I have indicated in Fig. 1, the electric 100 wires 27 and 28 are connected respectively to the terminal 12 and the conducting rod 25 for the purpose of conveying an electrical current to these parts and to the bent tube 29 supported on the shouldered contacts. Also at one end of this table I provide a knife- 105 switch 30 for the control of such current, preferably by the opening and closing of one of the circuits of an electric transformer.

To those skilled in this art it should be apparent that a bent tube, such, for example, as 110

the one characterized at 29 in the drawings, may be readily applied to the split terminals, the latter being expanded within its ends by the screws 18 to obtain an effective electrical connection between the parts, which enables me to send an electrical current of considerable amperage through the tube to heat the same during the application of the lacquer.

In order to adapt the appliance for the accommodation and reception of a shorter or longer tube, it is merely necessary to loosen the set-screw 26 and the nut 23, after which the movable terminal 20 may be slid in the slot 22 to the desired position, whereupon the operator, by tightening the screw 23 and the set-screw 26, is enabled to maintain this terminal in its new position and obtain a proper conductive connection between the same and the rod 25.

In a general way I have indicated the advantages of a construction of this kind, and have set forth with some degree of particularity a desirable embodiment of the invention, but it is to be understood that the latter is not necessarily limited and restricted to the precise construction shown, since many minor mechanical changes may be made without sacrificing the benefits and advantages of the invention, and without departure from its heart and substance.

I claim:

1. The combination of a pair of conductive split shouldered electrical terminals, a support therefor, and means to expand the split portions of said terminals within the ends of a tube to be lacquered, whereby an electric current may be sent through the tube

to heat the same during the application of the lacquer, substantially as described.

2. The combination of a pair of conductive split shouldered electrical terminals, a support therefor, one of said terminals being adjustable toward and from the other, means to hold said adjustable terminal in position with relation to the companion terminal, and means to expand the split shouldered portions of said terminals within the ends of a tube to be lacquered, whereby an electric current may be sent through the tube to heat the same during the application of the lacquer, substantially as described.

3. In a device of the character described, the combination of a slotted table, an electrical terminal fixed to said table, a companion electrical terminal adjustable toward and from the first terminal in said slot, means to hold said movable terminal in adjusted position, each of said terminals being conductive, split and having a shouldered portion, and a screw for each of said terminals having threaded engagement with one of the split portions thereof and adapted to bear against the companion split portion, whereby such screws may expand the split shouldered parts of the terminals within the ends of a tube to be lacquered, so that an electric current may be sent through the tube to heat the same during the application of the lacquer, substantially as described.

WILLIAM WRIGHT VINCENT.
